UNITED STATES PATENT OFFICE.

FRANK R. GIDDINGS, OF KALAMAZOO, MICHIGAN, ASSIGNOR OF ONE-HALF TO ALLAN M. GIDDINGS, OF BATTLE CREEK, MICHIGAN.

POPCORN HOLDER AND DISPLAY CABINET.

1,375,502.

Specification of Letters Patent. Patented Apr. 19, 1921.

Application filed March 29, 1920. Serial No. 369,615.

To all whom it may concern:

Be it known that I, FRANK R. GIDDINGS, a citizen of the United States, and a resident of Kalamazoo, in the county of Kalamazoo 5 and State of Michigan, have invented certain new and useful Improvements in Popcorn Holders and Display Cabinets, of which the following is a specification.

My present invention relates generally to 10 display devices, and more particularly to a display device in the nature of a pop-corn tank by which the pop-corn may be maintained in crisp and desirable condition and at the same time attractively displayed for 15 selling purposes.

The primary object of my invention is the provision of a device of this nature which will effectively perform the functions above stated, will be simple and inexpensive and 20 will obviate the necessity of attention.

In the accompanying drawings which illustrate my invention and form a part of this specification.

Figure 1 is a front elevation of my improved pop-corn tank,

Fig. 2 is a vertical section therethrough, and

Fig. 3 is a horizontal section taken on line 3—3 of Fig. 1.

Referring now to these figures my invention proposes a vertical cylindrical tank 10, which may be seated in elevated relation upon a frame 11 and which has in its curved wall at one side an enlarged transparent section 12 forming a window through which the contents may be viewed.

Opposite to the window 12 the tank has a door 13, which opens and closes upon hinges 14 and is provided with a latch 15 normally 40 holding the same in closed position.

The base 16 of the tank is closed and its inner surface is provided at diametrically opposite sides, between the window 12 and the door 13, with vertical series of spaced 45 brackets 17 forming supports for foraminous circular shelves 18, each preferably formed of reticulate material with a surrounding supporting ring 19, and each located it will be noted within full view 50 through the window 12.

On the base 16 beneath the lowermost shelf 18, are supported electric light bulbs 20 fed from a current supplying cord 21, provided with a plug 22 at its free end and 55 having branches 23 and 24. This cord 21

extends through an opening 25 in the conical top 26 of the tank, its branch 23 leading downwardly to the light bulbs 20 and its branch 24 leading upwardly to an upper light bulb 27 disposed within a removable 60 frame 28 at the apex of the top 26, within an inverted transparent bowl 29 which may be utilized to hold pop-corn for more or less permanent display purposes.

In the use of the tank, the freshly popped 65 corn is dumped upon the shelves 18 so that the heat generated by the bulbs 20 will circulate within the tank and through the popcorn on the shelves so as to maintain the latter in fresh crisp condition.

For this purpose access may be readily had to the tank through its door 13 opposite its display window 12, and it is thus obvious my invention provides a display device in which the interior is lighted and the 75 heat generated by the lighting means utilized to promote and maintain the proper condition of the commodity displayed.

It is also obvious that my invention provides a tank in connection with which supporting shelves may be readily shifted off of the supporting brackets 17 upon which they are loosely disposed, and the tank as a whole readily maintained in cleanly sanitary condition without difficulty.

It is further obvious my invention provides a display tank which will be inexpensive, which will avoid the necessity of frequent attention, and which will present a 90 pleasing appearance.

I claim:

1. A vertical cylindrical pop-corn tank having a window at one side, a hinged door opposite the window, vertical series of diametrically opposed brackets within the tank 95 between its window and its door, circular shelves of foraminous material loosely disposed upon the said brackets, and lighting means within the tank and disposed in the lower portion thereof whereby the heat generated by this lighting means will circulate through the several shelves and the material supported thereby.

2. A pop-corn tank having a conical top, a bulb supporting frame mounted at the 105 apex of said top, and a transparent bowl inverted over the said bulb supporting frame for the purpose described.

3. A pop-corn tank having at its top a frame adapted to support an electric light 110

- bulb, and a transparent bowl inverted over the said frame and in spaced relation thereto for the display of pop-corn within the bowl as described.
- 5 4. A pop-corn tank having a plurality of vertically spaced foraminous shelves, means within the lower portion of the tank to support electric light bulbs, and means to detachably support said shelves, said tank
- 10 having a window at one side through which the shelves may be seen and having a door

opposite the window through which access may be had to its interior as described.

5. A pop-corn tank having a vertical series of foraminous shelves and a window ¹⁵ through which the shelves may be viewed, and a source of light and heat below the shelves, the heat from which is free to pass upwardly through the shelves as and for the purpose described.

FRANK R. GIDDINGS.
